UNITED STATES PATENT OFFICE.

ELIZABETH S. CONDRA, OF CORONA, CALIFORNIA.

HAT-PIN.

No. 814,833.

Specification of Letters Patent.

Patented March 13, 1906.

Application filed August 22, 1904. Serial No. 221,630.

To all whom it may concern:

Be it known that I, ELIZABETH S. CONDRA, a citizen of the United States, residing at Corona, in the county of Riverside and State of California, have invented a new and useful Improvement in Hat-Pins, of which the following is a specification.

The main object of this invention is to provide a hat-pin that can be readily inserted or removed, but which when in place will not be liable to accidental displacement.

A further object of the invention is to provide a hat-pin that will engage with the wearer's hair to hold the pin in place.

Another object of the invention is to provide a hat-pin with means for engagement with the hat to hold the pin and hat in position.

The accompanying drawings illustrate the invention.

Figure 1 is a side view of one embodiment of my invention. Fig. 2 is a view showing the application of the pin.

In constructing a hat-pin in accordance with my invention a body 1 is formed from suitable material, preferably a small steel or iron rod of a length sufficient to pass entirely through the hat. One end of the body is sharpened to form a tip or point 2, adapted to be readily passed through the sides of the hat and also through the hair. A head or knob 3 is formed at the other end to form a means for manipulating the pin and to form a stop for preventing the pin from going too far.

The body of the pin is provided with a hat-coil of very few turns 4 and a hair-coil of many turns 4', the latter being located immediately adjacent to the tip 2 and the hair-coil being substantially midway between the hat-coil 4 and the head 3, so that when in place, as shown in Fig. 2, the hair-coil will lie exactly in the hair and the hat-coil will exactly engage the hat. The insertion of the pin is accomplished with the least possible manipulation, as the hat-coil 4 is first passed through one side of the hat, then through the hair, and then through the other side of the hat. After the hat-coil has passed through the first side of the hat by rotation the pin is pushed longitudinally without any rotation until the coil reaches the hair, when it is again rotated; but when it reaches the hair the second coil 4' has reached the side of the hat, so that the same rotation will carry one coil

through the hair and the other one through the side of the hat. The pin is then pushed longitudinally without rotation until the coil 4 reaches the other side of the hat, by which time the coil 4' has reached the hair, when the same rotation will carry the forward coil partly through the side of the hat and the other one into the hair and the head into engagement with the side of the hat where the pin was first inserted.

The two coils are arranged each with its axis substantially in a line with the straight or uncoiled portions of the pin, and the straight and uncoiled portions are also in line with each other, so that when the coils are being inserted there will be substantially no lateral movement of the main or straight portions of the pin, which would disarrange the hair, and by locating the first coil immediately adjacent to the tip and having the tip in a line with the axis of said coil the sharp end of the pin will not have to project so far through the side of the hat to have the coil engage therewith as would be the case if the coil were located at a distance from the tip, and the rotation of the pin when the coils are being inserted will be more uniform than if the tip were at one side of said axis.

From the foregoing it is evident that a pin constructed as above described can be made of any length and size and can be made as ornamental as desired, and yet the cost of construction will be substantially the same as for a straight or uncoiled pin, while it will be impossible for it to automatically work itself out of the hat and be lost, as so frequently happens with a straight pin.

Having described my invention, I claim—

A hat-pin comprising a metal rod having one end sharpened to form a tip or point, a head at the other end, the rod being provided with a hat-coil and a hair-coil, the hat-coil consisting of but extremely few turns and being located very close to the tip with its axis in line with the rod, the hair-coil consisting of many turns located midway between the head and the hat-coils and the axis of the hair-coils being in line with the rod.

In testimony whereof I have hereunto set my hand, at Corona, California, this 10th day of August, 1904.

ELIZABETH S. CONDRA.

In presence of—

EMMA A. MERCHANT,
C. G. TAYLOR.
